UNITED STATES PATENT OFFICE

CLAUDE F. TEARS, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR TREATING PETROLEUM OIL

Application filed June 18, 1923, Serial No. 446,057. Renewed February 23, 1929.

This invention relates to improvements in a process for treating petroleum oils, and refers more particularly to the destructive distillation of hydrocarbon oils to produce a product having the characteristics of gasoline and the like.

Among the objects of the invention are to provide a process in which a charging stock is treated to cracking conditions of temperature and pressure, subsequently the fractionated vapors being partially condensed and introduced at a reduced pressure to a rerun tower, in which they are relieved of their lighter fractions, which are finally condensed to produce a uniform high quality distillate.

The single figure is a diagrammatic side elevational view of the apparatus.

Referring to the drawing at 1 is shown a heating coil mounted in a furnace 2 which is connected by a transfer pipe 3 regulated by a valve 4 to an expansion chamber 5. The expansion chamber in turn is connected by a vapor line 6 controlled by a valve 7 to a dephlegmating column 8. The top of the dephlegmator is connected by a line 9 in which is interposed a valve 10 to a partial condensing coil 11 mounted in the condenser box 12. The discharge end of this coil is connected by means of a transfer pipe 13 controlled by an expansion valve 14 to the rerun tower 15. The rerun tower in turn is connected by a vapor line 16 regulated by a valve 17 to a final condenser 18 positioned in a condenser box 19, this final condenser being connected by a pipe 20 controlled by a valve 21 to the receiving tank 22.

In operation the charging stock is introduced through the line 23 controlled by a valve 24 from any convenient extraneous source, and is charged by means of the pump 25 through the line 26 to the heating coil 1 where it is raised to a conversion temperature under substantial pressure.

The oil on being discharged from the heating coil passes through the transfer line 3 into the expansion chamber 5 in which it is collected in a substantial body, the vapors evolved therein, passing off through the vapor line 6 to the dephlegmator, while the unvaporized products may be drawn off

through either of the residuum lines 26' regulated by the valves 25'.

The expansion chamber is equipped with try-cocks 27 for ascertaining the liquid level maintained therein. Upper and lower removable manhole plates on the chamber 5 furnish a means for cleaning the carbon accumulation resulting from the oil conversion. The vapors passing to the refluxing column rise, and in their travel are directed in a circuitous manner through the column due to the positioning of alternate baffle plates 28 at intervals in the column. These plates serve to promote a partial condensation of the higher boiling point fractions, which is further aided by the positioning of a cooling element in the upper portion of the column. This cooling element consists of a series of vertical open ended tubes 29 wedged into headers and positioned so that the vapors rise through the column and pass through the hollow tubes 29 while there is circulated around the tubes a cooling medium introduced through the pipe 31 and withdrawn through the line 30.

Oil or other liquid mediums may be utilized to produce this cooling action. The condensate separated out from the vapors during their travel through the fractionating or dephlegmating column collects in the bottom, and is drawn off through the lower leg of the dephlegmator 32 through the line 33 to be recycled with the charging stock to the heating stage. The overhead vapors passing from the top of the dephlegmator are directed through the line 9 to a partial condenser where their temperature is somewhat reduced, and a partial condensation takes place. The purpose of this partial condenser is to cool the vapors prior to their introduction to the rerun tower or fractionating column. The discharge end of the partial condenser has connection with the rerun tower

15 as explained, by transfer pipe 13 in which is interposed an expansion valve controlled 95 to relieve the pressure maintained upon the fluid discharge from the partial condenser to a pressure slightly above atmospheric. These fluid and vaporous hydrocarbons are introduced centrally of the rerun tower which is 100

preferably of a form diagrammatically disclosed in the drawing consisting of a well known type of bubble tower which is equipped with a plurality of decks 34 positioned at different levels in the tower, and 5 having standpipes communicating between the separate levels to maintain separate pools of liquid levels on the respective decks. Cap risers such as those shown at 35 furnish a means for the vapors from the levels below 10 to percolate through the pools of oil as they rise to the top of the column.

The rerun tower is preferably heavily insulated, and has a lower compartment 36 in 15 which the liquid condensate collects, and in which is positioned a perforated steam coil 36^a by means of which superheated steam is introduced to the tower to promote vaporization therein. In place of the steam coil, the 20 lower portion of the tower may be enclosed in a furnace construction externally heated to produce vaporization of the condensate collecting in the lower portion 36. A substantial body of liquid oil may be maintained in the 25 lower portion 36 by suitably regulating the valves 43, 44 and 45 in the drawoff lines 46 and 47, as well as by regulating the valves 48 and 49 in the liquid level control device 50. With the release of pressure on the oil as it 30 is desired from the partial condenser, the fluid hydrocarbons will expand, certain fractions vaporizing and passing to the top of the column while other higher boiling point fractions will find their way to the lowest compartment 36 where they will be subjected to 35 the increased temperature conditions maintained therein. The vapors rising to the top of the rerun tower pass over to the line 16 regulated by a valve 17 and are finally condensed in the condensing coil 18, after which 40 they are collected as liquid distillate in the receiver 22. The receiver is equipped with a pressure relief valve 37, a pressure gauge 38, a liquid level gauge 39 and a liquid drawoff valve 40.

45 To obtain the desired temperature at the top of the rerun tower, controlled portions of the liquid distillate may be withdrawn from the receiving tank 22 and recycled by means of the pump 41 and return line 42 regulated by a valve 42' to supply the liquid distillate into the top of the rerun tower, thereby returning sufficient amounts of the liquid distillate to maintain the desired temperature at 50 the top of the tower and further supply a liquid medium to the tower which has the effect of retarding the passage of certain heavy objectionable fractions which would otherwise pass over to the receiver and form 55 an objectionable constituent in the final distillate.

It is to be noted that the feed to the tower is introduced at a point intermediate between the top and bottom. The vapor from 60 the dephlegmator is led through a cooler

where it is cooled and partially condensed, then the pressure is released and the hot vapor and liquid enters the rerun tower where the gasoline is distilled off leaving pressure distillate bottoms to flow off as residue from the bottom of the rerun tower. A portion of the final condensate is returned to the top of the rerun tower as refluxing medium. In order to strip the pressure distillate bottoms of gasoline it will probably be necessary to provide heat at the bottom of the tower and for this purpose saturated or superheated steam may be injected into the lower section of the tower as shown in the sketch. It is also possible to supply this heat 75 by means of a fire heated still which may take the form of a pipe or tube still separately fired or located in the flues of the cracking unit where waste heat will be recovered.

80 Since by use of this scheme there will be no pressure distillate condensate to recirculate to the top of the dephlegmator, it is necessary to provide some other means of refluxing and it is proposed to incorporate a partial condenser in the top of the dephlegmator. This condenser will be in the form of a tubular condenser, as shown in the sketch, or a coil condenser and may employ as a cooling medium either water or raw oil entering 85 the system.

85 As an illustrative run, a Mid-Continent gas oil having a Baume gravity of 31° was introduced and heated to a temperature of from 700° to 900° F., in the heating coil, thence 90 passed to the expansion chamber, and the vapors dephlegmated in the column 8 as explained. The temperature of the vapors leaving the top of the dephlegmator was substantially 550° F. The temperature of the vapors leaving the cooler between the dephlegmator 95 and rerun tower ranged from 400° to 500° F., while the temperature at the top of the rerun tower was substantially 350° F. The temperature at the bottom of the rerun tower using superheated steam was substantially 100 450° F., while if extraneously heated a temperature of 550° is advisable. The pressure during operation upon the cracking portion of the still was substantially 125 pounds per square inch. Under these conditions a high 105 quality of Navy specification distillate was 110 produced in the receiving tank 22.

115 I claim as my invention:

1. An oil conversion process, consisting in 120 subjecting the oil to cracking conditions of temperature and pressure, in subjecting the evolved vapors to reflux condensation in a reflux condenser, in re-cracking the reflux condensate, in passing the vapors from the 125 reflux condenser to a partial condenser, in fractionating the vapors and liquid passing from the partial condenser, in introducing steam to the vapors and liquid undergoing fractionation, and in condensing and collect- 130

ing the uncondensed vapors after fractionation as gasoline-like products.

2. A continuous oil conversion process, consisting in subjecting the oil to cracking conditions of temperature and pressure in a cracking zone, in continuously passing the generated vapors from said cracking zone to a dephlegmator, in returning reflux condensate from said dephlegmator to the cracking zone, in passing the dephlegmated vapors from said dephlegmator to a primary condenser wherein only a portion of the vapors are condensed, in passing the uncondensed vapors and distillate to a zone of fractionation maintained under a reduced pressure, and in introducing into said zone of fractionation steam to commingle with the vapors and distillate therein, in condensing the fractionated vapors, and in collecting the resulting gasoline-like product.

3. A continuous oil conversion process, consisting in subjecting the oil to cracking conditions of temperature and pressure in a cracking zone, in continuously passing the generated vapors from said cracking zone to a dephlegmator, in returning reflux condensate from said dephlegmator to the cracking zone, in passing the dephlegmated vapors from said dephlegmator to a partial condenser from which the vaporous and liquid constituents are passed to a zone of fractionation maintained under a reduced pressure, in introducing into said zone of fractionation steam to commingle with the vaporous and liquid constituents therein, in condensing the fractionated vapors, in collecting the resulting gasoline-like product, and in returning portions of said product to said fractionating zone to be re-vaporized therein.

4. A hydrocarbon oil cracking process which comprises subjecting the oil to cracking conditions of temperature and pressure and separating evolved vapors from unvaporized oil, dephlegmating said vapors to condense fractions thereof substantially heavier than gasoline while retaining the gasoline-like pressure distillate in vaporous form, subsequently cooling the uncondensed vapors to a temperature between 400° F. and 500° F. and reducing the pressure thereon to slightly above atmospheric, introducing the resulting liquid and vaporous hydrocarbons into a fractionating zone for fractionation therein, applying a distillation heat to the lower portion of said fractionating zone, maintaining in the upper portion of said zone a temperature sufficient to permit gasoline-like hydrocarbons to pass therefrom in vaporous form, removing gasoline-like vapors from the upper portion of said zone and subjecting the same to condensation.

5. A hydrocarbon oil cracking process which comprises subjecting the oil to cracking conditions of temperature and pressure and separating evolved vapors from unva-

porized oil, dephlegmating said vapors to condense fractions thereof substantially heavier than gasoline while retaining the gasoline-like pressure distillate in vaporous form, subsequently cooling the uncondensed vapors to a temperature between 400° F. and 500° F. and reducing the pressure thereon to slightly above atmospheric, introducing the resulting liquid and vaporous hydrocarbons into a fractionating zone for fractionation 70 therein, applying a distillation heat to the lower portion of said fractionating zone, maintaining in the upper portion of said zone a temperature sufficient to permit gasoline-like hydrocarbons to pass therefrom in vaporous form, removing gasoline-like vapors from the upper portion of said zone and subjecting the same to condensation thereby forming condensate, and returning a portion 80 of said condensate to said fractionating zone. 85

6. A hydrocarbon oil cracking process which comprises subjecting the oil to cracking conditions of temperature and pressure and separating evolved vapors from unvaporized oil, dephlegmating said vapors to condense fractions thereof substantially heavier than gasoline while retaining the gasoline-like pressure distillate in vaporous form, subsequently partially condensing the uncondensed vapors, whereby only a portion 90 of the gasoline-like vapors are condensed, introducing the resulting liquid and vaporous hydrocarbons into a fractionating zone for fractionation therein, applying a distillation heat to the lower portion of said fractionating zone, maintaining in the upper portion of said zone a temperature sufficient to permit gasoline-like hydrocarbons to pass therefrom in vaporous form, removing gasoline-like vapors from the upper portion of said zone and subjecting the same to condensation. 100

7. A hydrocarbon oil cracking process which comprises subjecting the oil to cracking conditions of temperature and pressure and separating evolved vapors from unvaporized oil, dephlegmating said vapors to condense fractions thereof substantially heavier than gasoline while retaining the gasoline-like pressure distillate in vaporous form, subsequently cooling the uncondensed vapors to a temperature between 400° F. and 500° F. and reducing the pressure thereon to slightly above atmospheric, introducing the resulting liquid and vaporous hydrocarbons 110 into a fractionating zone for fractionation therein, simultaneously introducing steam to the lower portion of said fractionating zone, maintaining in the upper portion of said zone a temperature sufficient to permit gasoline-like hydrocarbons to pass therefrom in vaporous form, removing gasoline-like vapors from the upper portion of said zone and subjecting the same to condensation. 115

8. A process for cracking hydrocarbon oil 130

which comprises subjecting the oil to cracking conditions of temperature and pressure thereby forming a vaporous hydrocarbon mixture, dephlegmating said vaporous mixture to condense fractions thereof substantially heavier than gasoline while retaining the gasoline-like pressure distillate in vaporous form, passing the vaporous pressure distillate to a cooling zone and lowering the temperature thereof at least 100° F. in said zone, thereby condensing a portion of said distillate, removing the pressure distillate from said zone and introducing the same to a fractionating zone for fractionation therein, applying a distillation heat to the lower portion of said fractionating zone, maintaining in the upper portion of said zone a temperature sufficient to permit gasoline-like hydrocarbons to pass therefrom in vaporous form, removing gasoline-like vapors from the upper portion of said zone and subjecting the same to condensation.
